W. H. HAMPSON.
PIPE COUPLING.
APPLICATION FILED AUG. 1, 1919.

Patented Nov. 30, 1920.

Inventor:
William H. Hampson,
by his attorney,

Charles S. Gooding.

UNITED STATES PATENT OFFICE.

WILLIAM H. HAMPSON, OF BELMONT, MASSACHUSETTS.

PIPE-COUPING.

1,360,633.

Specification of Letters Patent. Patented Nov. 30, 1920.

Application filed August 1, 1919. Serial No. 314,612.

To all whom it may concern:

Be it known that I, WILLIAM H. HAMPSON, a citizen of the United States, residing at Belmont, in the county of Middlesex and State of Massachusetts, have invented new and useful Improvements in Pipe-Couplings, of which the following is a specification.

This invention relates to an improved coupling for pipes and is particularly adapted for use in the coupling of the air line hose between cars on railroad trains.

The object of the invention is to provide a simple and efficient means for locking the two heads of a pipe coupling together in such a manner that they may be easily and automatically disengaged one from the other when the cars to which they are attached are uncoupled.

20 The invention consists in the combination and arrangement of parts set forth in the following specification and particularly pointed out in the claims thereof.

Referring to the drawings:

25 Figure 1 is a side elevation of a pipe coupling embodying my invention.

Fig. 2 is an enlarged side elevation of one of the coupling heads.

30 Fig. 3 is a sectional elevation taken on line 3—3 of Fig. 1.

Fig. 4 is a sectional elevation taken on line 4—4 of Fig. 1.

Fig. 5 is a side elevation of another coupling head.

35 Like numerals refer to like parts throughout the several views of the drawings.

The general style of coupling to which my improvement is particularly adapted and illustrated in the drawings and herein-40 after described in the specification is well known to those skilled in the art and is similar to the style of coupling set forth in the patent to C. Forth, No. 1,035,564, to which for further detailed illustration reference may be had.

45 In the drawings 6 and 7 are the two coupling heads. Said coupling heads are provided with lateral ports 8 and 9, respectively, in alinement with each other and with gaskets 10 and 11, which, when the parts of the coupling are in operative position, are in engagement with each other. The heads 6 and 7 as illustrated are preferably counterparts of each other and when 55 in operation are reversibly positioned relatively to each other.

The head 6 is provided with a segmental flange 12 which is provided at one end thereof with a laterally extending rib 13. Diametrically opposed to the segmental flange 60 12 is another segmental flange 14 which has a laterally extending rib 15 concentric with the head 6 and extending across the entire length of the flange 14.

It will be seen that the flanges 12 and 14 65 are continuous and that the rib 13 is substantially shorter than the rib 15.

The head 7 has a segmental flange 16 thereon, from which projects laterally a rib 17 and diametrically opposed to the flange 70 16 is another segmental flange 18 which is provided with a rib 19 extending throughout the entire length of said flange 18. It will be seen that the rib 17 is substantially shorter than the rib 19.

75 When the parts are locked together in operative position as in Fig. 1, the center line A of the head 6 is at an angle to the center line B of the head 7, and when in this position, as illustrated in Fig. 3, the rib 13 of the head 6 is interlocked with the rib 19 of the head 7 and the rib 17 of the head 7 is interlocked with the rib 15 of the head 6, and furthermore, the rib 13 engages the flange 18 and the rib 17 engages the 85 flange 14.

80 When the heads 6 and 7 are rotated, either by hand or by a pull upon the hose caused by the cars being uncoupled and separating, so as to bring the center lines A and B substantially in alinement with each other, or parallel to each other, it will be seen that the head 6 will rotate in the direction of the arrow α (Fig. 1) and that the head 7 will rotate in the opposite direction, and when 90 said heads have rotated a distance substantially equal to or slightly greater than the length of the rib 13, the rib 13 will be out of engagement with the rib 19 and the rib 17 will be out of engagement with the rib 15, so that the parts are then free to separate upon a longitudinal pull being imparted thereto.

95 The general operation of the device is as follows: The heads are positioned with the center lines thereof in alinement or parallelism and with the gaskets 8 and 9 pressed together. Then the head 6 is rotated in the opposite direction to the arrow α and the head 7 is rotated in the direction of the arrow α (Fig. 1), and the parts then assume 105 the relative positions illustrated in Fig. 1.

When the cars are uncoupled the pull upon the hose will automatically cause the heads 6 and 7 to rotate upon each other, the head 6 in the direction of the arrow *a* and the head 7 in the opposite direction to that of the arrow *a*, and as soon as the ribs 13 and 17 have passed out of engagement with the ribs 19 and 15 the two heads 6 and 7 will become disconnected.

10 Having thus described my invention, what I claim and desire to secure by Letters Patent is:

1. A pipe coupling having, in combination, a pair of oppositely disposed heads rotatably mounted upon each other, each of said heads having a lateral port opening in alinement with a lateral port opening on the other head, a continuous segmental flange on diametrically opposite sides of each of said heads, each of said flanges having a laterally extending rib thereon, the ribs on the flanges of one head being adapted to interlock with the ribs on the flanges adjacent thereto on the other head, one rib of each pair of said interlocking ribs being shorter than the other rib of said pair and substantially shorter than its respective flange, whereby when one of said heads is rotated upon the other for a portion of the length of said longer ribs said heads will become unlocked from each other.

2. A pipe coupling having, in combination, a pair of oppositely disposed heads rotatably mounted upon each other, said heads being counterparts of each other and reversibly positioned relatively to each other, each of said heads having a lateral port opening in alinement with a lateral port opening on the other head, a continuous segmental flange on diametrically opposite sides of each of said heads, each of said flanges having a laterally extending rib thereon, the ribs on the flanges of one head being adapted to interlock with the ribs on the flanges adjacent thereto on the other head, one rib of each pair of said interlocking ribs being shorter than the other rib of said pair and substantially shorter than its respective flange, whereby when one of said heads is rotated upon the other for a portion of the length of said longer ribs said heads will become unlocked from each other.

3. A pipe coupling having, in combination, a pair of oppositely disposed heads rotatably mounted upon each other, each of said heads having a lateral port opening in alinement with a lateral port opening on the other head, a continuous segmental flange on diametrically opposite sides of each of said

heads, each of said flanges having a laterally extending rib thereon, the ribs on the flanges of one head being adapted to interlock with the ribs on the flanges adjacent thereto on the other head, one of said ribs on one head being shorter than the other rib on said head and substantially shorter than its respective flange, the shorter rib on each head interlocking with the long rib of the other head, whereby when one of said heads is rotated upon the other for a portion of the length of said longer ribs said heads will become unlocked from each other.

4. A pipe coupling having, in combination, a pair of oppositely disposed heads rotatably mounted upon each other, each of said heads having a lateral port opening in alinement with a lateral port opening on the other head, a continuous segmental flange on diametrically opposite sides of each of said heads, each of said flanges having a laterally extending rib thereon, the ribs on the flanges of one head being adapted to interlock with the ribs on the flanges adjacent thereto on the other head, one of said ribs on one head being shorter than the other rib on said head and substantially shorter than its respective flange, the shorter rib on said head interlocking with the long rib of the other head, said shorter ribs being located at the same ends of their respective flanges, whereby when one of said heads is rotated upon the other for a portion of the length of said longer ribs said heads will become unlocked from each other.

5. A pipe coupling having, in combination, a pair of oppositely disposed heads rotatably mounted upon each other, each of said heads having a lateral port opening in alinement with a lateral port opening on the other head, a continuous segmental flange on diametrically opposite sides of each of said heads, each of said flanges having a laterally extending rib thereon, the ribs on the flanges of one head being adapted to interlock with the ribs on the flanges adjacent thereto on the other head, one rib of each pair of said interlocking ribs being shorter than the other rib of said pair and substantially shorter than its respective flange and adapted to engage said flange, whereby when one of said heads is rotated upon the other for a portion of the length of said longer ribs said heads will become unlocked from each other.

In testimony whereof I have hereunto set my hand.

WILLIAM H. HAMPSON.
